ELECTRICAL SELECTING OR CONNECTING DEVICE

John Fredrik Teodor Engblom, Nottingham, England, assignor to Ericsson Telephones Limited, London, England

Application December 29, 1931, Serial No. 583,720
In Great Britain February 28, 1931

1 Claim. (Cl. 235—92)

5 My invention relates to electric selecting or connecting devices consisting of a plurality of suitably connected relays. Examples of such devices are those known in automatic telephony as relay chains. The connections of the relay operating coils and contacts are usually such that the relays, or those of them that are required to operate in particular circumstances, operate in a particular order.

10 A disadvantage of known arrangements is the presence of a large number of contacts the proper functioning of each of which is essential to the operation of the device as a whole. An object of my invention is to reduce the number of such contacts.

15 My invention relates particularly to devices adapted to make a non-numerical selection, for example, to connect calling lines in turn to apparatus to which they are to be extended. It 20 has a special application in a totalizer system in which it is required to make common registering apparatus, or conductors leading thereto, available to a plurality of ticket issuing or like machines.

25 In my invention I use, in place of a simple series of relays, a compound arrangement consisting of two or more groups of relays, each group being similar to (but less in number than) the simple series which the compound arrangement displaces. I apply an operating potential to any one relay, but to not more than one at a time, by extending the operating potential to one of the groups and thence to a particular relay in that group. To this end, I may provide a chain 30 of serially-related contacts comprising a main portion and a number of branch portions so that the number of serially-related contacts through which the operating potential must pass to reach the most unfavorably situated relay is substantially less than the number of relays. Further, I may perform the actual selection (for example, the connection of a particular ticket issuing machine in a totalizer to common registering apparatus) according to a combination of relays 35 operated at the same time.

40 By these means the number of serially-related sections in one group of relays can be reduced to approximately the square (or higher) root of the number of different selections to be made. 45 The total number of contacts the failure of which would interrupt the operation of the whole device can therefore be considerably reduced.

45 The invention can be applied with advantage to a totalizer system of the kind in which a potential is extended through contacts of relays

5 associated with ticket-issuing machines having no bets to be collected to a winding of a relay associated with the next machine having a bet to be collected. Such a system (not embodying the present invention) is shown for explanatory purposes in Figure 3. In this figure, the circuits enclosed within dotted rectangles are individual to ticket issuing machines and it is assumed that when a particular machine has a bet to be collected, the appropriate relay ST, ST¹ . . . STⁿ is 10 operated. Relay BS is common to all the machines and is assumed to be operated whenever betting is in progress. When, for example, relay ST¹ is operated, contact st¹₃ connects relay A¹ to earth via contacts st₂ and bs₁ and the winding of relay CT (in parallel with resistance R₁). The other side of the upper winding of relay A¹ is connected to negative battery (not shown) and relay A¹ operates to cause the bet to be collected. Contact a¹₃ extends the earth from contact bs₁ 20 to succeeding machine circuits (from which it has been temporarily disconnected by contact st¹₃).

15 The circuit just described forms part of the system shown in the specification of British Patent No. 368,445 dated January 2nd, 1931, and the specification of the corresponding U. S. Patent No. 2,007,402 dated July 9, 1935, which includes many details not necessary to an understanding 25 of the present invention.

20 In the application of the present invention to a system of the above-mentioned kind, the machines would be divided into groups, and the relay chain would be employed to extend a potential through contacts associated with groups having no bets to be collected to a chain of contacts associated with the next group having a bet to be collected, and thence through contacts associated with machines in that group having 30 no bets to be collected to a winding of a relay associated with the machine having a bet to be collected. The number of series contacts through which current would have to pass would therefore be considerably reduced and the chance of failure 35 owing to a faulty contact correspondingly decreased.

35 In order that my invention may be readily understood examples of its application will now be given and reference should be made to the accompanying drawings, which show modifications of the totalizer system described in the aforementioned British specification.

40 Figure 1 shows an arrangement that I term a two co-ordinate chain and

Figure 2 one that I term a four co-ordinate chain, both according to my invention.

Figure 3 represents an arrangement forming part of a previous invention described in the specification of British Patent No. 368,445 dated January 2nd, 1931 of which the present invention is a development or modification.

In Figure 3, which represents the portion of the invention described in the prior specification above referred to relevant to the present invention, there is shown as described above a relay chain comprising relay contacts $st3$, $st'3$ . . . st^n3 , $a3$, $a'3$ . . . a^n3 and relays ST , ST' . . . ST^n and A , A' . . . A^n . The chain circuit is completed 10 by a relay CT , resistance $R1$, contact $bs1$ and resistance $R2$. This arrangement constitutes what I may term a single co-ordinate chain, that is, a chain in which the location of any ticket issuing machine is completely determined by its 15 distance from one end of the chain. Thus, the machine controlled by relay A is the first machine and that controlled by relay A' is the second machine.

Figure 1 of the drawings accompanying the 20 present specification shows the modifications necessary to replace the single co-ordinate chain by a two co-ordinate chain.

As in the case of the earlier specification, the apparatus individual to a ticket-issuing machine includes a relay A , a relay ST , and a relay HO . Relay ST is operated when a key is pressed 25 to send a signal from the machine to common registering equipment. Its object is to start the train of operations which result in the registration of the signal and the issue of a ticket by the machine, and on this account we will term it a start relay. Relay A is operated when the registering equipment is ready to receive the signal, and its object is to transmit the signal thereto. 30 We will therefore term relay A a signal sending relay. Relay HO , which we will term a hold-off relay, operates after the signal has been transmitted, and its object is to prevent the re-operation 35 of relay ST for the transmission of further signals by the machine in question until other machines which may be waiting to transmit signals have had an opportunity of taking the common registering equipment into use. The circuit arrangements whereby these relays perform 40 their functions are more fully described in the earlier specification.

In addition to the apparatus individual to each ticket-issuing machine, the present drawing shows a relay CT , resistance $R1$, contact $bs1$ and 45 resistance $R2$. These pieces of apparatus also correspond to similarly designated pieces of apparatus in the earlier case. The circuit from contact $bs1$ to resistance $R2$, however, instead of being completed through contacts $st3$, $st'3$ . . . st^n3 after 50 st^n3 is normally completed through contacts $sa1$, $sb1$ . . . $sn1$ of relays SA , SB . . . SN respectively, and only passes through contacts $st3$, $st'3$ . . . st^n3 after one of said contacts $sa1$, $sb1$ . . . $sn1$ has been 55 operated. The operation of any one of these relays is adapted to extend the earth potential from relay CT to a group of ticket issuing machine circuits represented by the dotted rectangles O , I , . . . n . Thus, the operation of relay SA extends the earth potential to the top row of circuits, the operation of relay SB extends it to the 60 second row, and so on. There may, of course, be any desired number of rows and any desired number of machines in each row.

In the ticket machine circuits, relays such 65 as A and contacts such as $st3$ and $a3$ correspond

to the similarly designated parts in the previous invention represented in Figure 3. Similarly the ticket issuing machine circuit represented by rectangle O incorporates a relay A' , and contacts $st1$, $st'3$, $a'1$, $a'3$ and $ho2$, while that represented by rectangle n incorporates relay A^n , and contacts such as st^n1 , st^n3 etc. Each of these series-connected machine circuits corresponds to, and operates in the same way as, a like circuit represented by one of the dotted rectangles shown in Figure 3 described above. Separate relays SA , SB . . . SN are provided, one for each group of machines. These relays are operated via contacts such as al and $st1$ and close, at contacts $sa2$, $sb2$ . . . $sn2$, the hold-off circuits 15 to contacts such as $ho2$ in the ticket machine circuits.

These modifications do not affect the circuit individual to the ticket machine. The operation of a relay such as SA , however, besides performing holding functions also extends the earth potential from relay CT to the required group of machines, whence it is extended by the contact such as $st3$ of the machine having its ST relay operated to the appropriate A relay. 20

Machines whose contacts $st3$ are nearer to the operating potential have precedence over machines whose contacts $st3$ are further away. In addition, groups of machines whose contacts $sa1$, $sb1$ . . . are nearer to the operating potential have 25 precedence over machines whose contacts $sb1$ . . . $sn1$ are further away. It is impossible, therefore, for the operating potential to be extended simultaneously to two or more A relays, even though several ST relays and several of relays SA , SB . . . SN may be operated at the same time. There is, moreover, provision for preventing a machine that has been made effective from being made effective again until other waiting machines have had their turn, since the operation of any of 30 $relays SA, SB . . . SN$ maintains the hold-off circuits via contacts $ho2$ of the machines that have had their turns. This feature does not form part of the present invention and will not therefore be described in detail. 40

In the modification shown in Figure 2 of the accompanying drawings, relay CT , resistance $R1$, contact $bs1$ and resistance $R2$ correspond to the similarly designated parts in Figure 1. Relays SA , SB and SC , contacts $sa1$, $sb1$ and $sc1$, and 45 contacts $sa2$, $sb2$ and $sc2$ correspond to relays SA , SB . . . SN , contacts $sa1$, $sb1$ . . . $sn1$, and contacts $sa2$, $sb2$ . . . $sn2$ respectively. The machines, however, instead of being subdivided into groups only once, are subdivided three times. The first 50 subdivision is into three groups controlled by relays SA , SB and SC and it will be observed that the operation of relay SA , for example, extends the earth potential from relay CT to contacts $ta1$ and $tb1$ of relays TA and TB . 55 Similar relays (not shown) are provided for the groups controlled by relays SB and SC . According to whether one, or the other, or neither of relays TA and TB is operated, the earth potential is further extended to one of three pairs of contacts such as $ua1$ and $ub1$ of relays UA and UB . According to whether one, or the other, or neither of relays UA and UB is operated, the earth potential is further extended to one of three groups of machines, for example, to the group represented 60 by the top three rectangles in the figure. The machine of the group which is made effective depends, as in Figure 1, upon which ST relay is operated, the circuits individual to the machines being identical with those already described. 65

5 The operation of any ST relay causes the operation of the appropriate relays such as SA, TA and UA for extending the earth potential to its own group. The arrangement is such that the earth potential cannot be extended to more than one machine at once, even if several relays such as ST, UA, TA and SA are operated at the same time. Since the hold-off circuit to contacts h_02 is maintained by any of relays SA, SB or SC, a 10 machine is prevented from being made effective twice while another machine that has not had its turn is waiting.

10 In the arrangement described, there would be one set of contacts sa^1 , sb^1 and sc^1 , there sets 15 such as those on relays TA and TB, nine sets such as those on relays UA and UB and 27 sets of three machines, that is, eighty-one machines in all. These numbers may, of course, be varied in any 20 suitable manner according to the number of machines to be accommodated and the number of stages of subdivision. An increase in the number of stages of subdivision will generally result in a reduction in the number of series contacts which 25 must be passed through in order to reach the most unfavourably situated machine.

25 In Figure 2, instead of relays such as SA, TA and UA being operated in series, there may, if desired, be separate contacts such as st^1 for operating each of the relays required to extend the 30 earth potential to a particular group of machines.

Although my invention has been described in conjunction with particular circuits I do not limit it thereto, and may make considerable modifications in the method of carrying it out without

departing from its spirit as set out and claimed.

Having now described my invention, what I claim as new and desire to secure by Letters Patent is:—

Electrical selecting arrangements in the signaling system of a totalizer comprising a plurality of start relays, a plurality of signal sending relays, and a plurality of hold-off relays, corresponding relays in each plurality being associated to form sets of three relays, the said sets of relays being 5 associated in groups of sets, a group relay associated with each of the said groups, a circuit for each of the said group relays closed upon the operation of any start relay in the associated group and opened upon the operation of the corresponding signal sending relay, means for extending an operating potential to any one of the said signal sending relays, said means comprising a chain of serially related contacts having a trunk 10 portion comprising contacts of the said group 15 relays and branch portions comprising contacts of the said start relays, each of the said group relays having a contact which controls the release of such of the said hold-off relays as are comprised within the corresponding group, so that 20 after the operation of any given signal sending relay and the subsequent operation of the associated hold-off relay the said hold-off relay is maintained energized so long as any start relay 25 in the same group remains operated without the 30 operation of the corresponding signal sending relay.

JOHN FREDRIK TEODOR ENGBLOM.
